DOOR CLEANING APPARATUS
 Morton M. Rosenfeld, Mount Vernon, N.Y.
 (271 Madison Ave., New York, N.Y.)
 Filed Nov. 24, 1961, Ser. No. 154,545
 2 Claims. (Cl. 109—1)

This invention relates to a door cleaning apparatus. More particularly, this invention relates to a door cleaning apparatus for doors on bomb shelters, air-raid shelters, and other types of enclosures or buildings which are intended to prevent persons from dust, radioactive fallout dust, explosive blasts, etc.

The door cleaning apparatus of the present invention may be utilized on a wide variety of structures. For purposes of illustration, the door structure will be a part of a blast shelter. Preferably, the door structure will be provided with means for providing communication between the interior of the enclosure and the surrounding atmosphere. Such means may be in the nature of a filter mounted within an opening in the door.

Heretofore, there has been no means provided to remove dust such as radioactive dust which has settled on the door and the surrounding portions of the walls defining the enclosure. In accordance with the present invention, means are provided to flush the outer surface of the door with a liquid. The flushing may be controlled from a position within the enclosure. Means are provided to receive the flushing liquid and any dust associated therewith.

It is an object of the present invention to provide a novel means for cleaning a door.

It is another object of the present invention to provide a blast shelter with a door cleaning apparatus.

It is another object of the present invention to provide a door structure with means for cleaning the same and receiving the cleaning liquid.

It is another object of the present invention to provide a door structure having a filtered aperture therein with means for receiving contaminated filters and a liquid for cleaning a surface of a door.

Other objects will appear hereinafter.

For the purpose of illustrating the invention there is shown in the drawings a form which is presently preferred; it being understood, however, that this invention is not limited to the precise arrangements and instrumentalities shown.

FIGURE 1 is an elevation view of a bomb shelter having a door structure and door cleaning apparatus in accordance with the present invention.

FIGURE 2 is a sectional view taken along the lines 2—2 in FIGURE 1.

FIGURE 3 is a sectional view taken along the lines 3—3 in FIGURE 1.

Referring to the drawing in detail, wherein like numerals indicate like elements, there is shown in FIGURE 1 a bomb shelter designated generally as 10.

The bomb shelter 10 may be an aboveground structure, an underground structure, or a structure constructed within the corner of a basement of a building. The bomb shelter 10 includes a concrete floor 12 and a ceiling 14 supported above the floor 12 by means of walls 16. One of the walls 16 is provided with a doorway 18 extending up from the floor 12.

A door 20 is pivotally mounted in the doorway 18 by means of hinges 22 and 24. A seal 26 is provided around the periphery of the door 20. The seal 26 is shielded from direct radiation by means of a lip around the doorway 18 and a water barrier 28 extending upwardly from the floor 12.

A flow passage 30 is disposed in the floor 12 between

2

the inner surface of the water barrier 28 and the door 20. The passage 30 communicates with a chamber 32 therebelow.

A container 34 is mounted above the doorway 18. The container 34 is provided with a fill spout 36. The fill spout 36 is selectively closed by means of a pivotable lid 38. The container 34 is adapted to contain a flushing liquid such as water, mixtures of water and bleaching or neutralizing agents, etc.

The container 34 is provided with a discharge conduit depending therefrom. The conduit 40 is provided with a valve 42. The valve 42 selectively controls flow through the conduit 40. The movable element within the valve 42 is selectively controlled by means of a valve actuator 44. The valve actuator 44 may be in the nature of a flexible wire, chain, rope, or the like which terminates in a knob or ring within the bomb shelter 10.

A gutter 46 is adjustably secured adjacent the top of the outermost wall of the door 20 in a manner so that it slopes from one side and extends across the door 20. The bottom wall of the gutter 46 is provided with a plurality of holes 48 through which the liquid may flow.

The door 20 is preferably made of a concrete material with elements having shielding characteristics disposed uniformly therein. Such elements may include a wide variety of shielding materials such as lead, carbon, etc. In this manner, the door 20 will have substantially the same shielding characteristics as the walls 16. The door 20 is provided with an opening 52. A filter 54 is removably secured within the opening 52. The filter is preferably provided with tabs 56 which facilitate handling and mounting of the filter 54. The filter 54 is snap-fitted within the opening 52.

Filters 54 are inserted in snap-fitted engagement with the opening 52 from a position inside the bomb shelter 10. The tabs 56 are preferably readily removable from the filter 54. By removing the filter tabs 56 and applying pressure therewith against the filter 54, the filter 54 may be pushed outwardly into a position juxtaposed to the filter guard 50. Thereafter, the filter 54 will be directed in a path so that it falls due to gravity, bounces off the splash plate 58, through the passage 30 into the chamber 32. In order to prevent the passage of unfiltered air into the bomb shelter 10, the existing filter 54 may be pushed from its snap-fitted engagement within the opening 52 by means of a new filter 54. Hence, the opening 52 will be provided with a filter at all times.

The filter guard 50 may be made from any one of a wide variety of materials capable of enabling the guard 50 to protect the filter. As shown, the filter guard 50 is made from a fine wire mesh material. The filter guard 50 must lack a bottom wall or be provided with a bottom wall having a slot therein so that the filters 54 may pass therethrough. The splash plate 58 assists in guiding the filters 54 and flushing liquids into the passage 30.

When it is desired to flush the outer surface of the door 20, a person from within the bomb shelter 10 need only pull on the actuator 44. Tension in the actuator 44 opens the valve 42 thereby permitting flushing liquid to flow from the container 34 into the gutter 46. The gutter 46 is tilted as shown more clearly in FIGURE 1 so that the liquid flows along the entire length thereof. The liquid flows from the gutter 46 through the holes 48 down the surface of the door 20 thereby flushing off any accumulated dust. The mixture of flushing liquid and dust is guided by the splash plate 58 into the passage 30. The chamber 32 is of sufficient capacity so that it may accommodate all of the flushing liquid and dirty filters introduced therein during a thirty (30) day period. If desired, the size of the chamber 32 may be increased or decreased to accommodate longer or shorter periods of use.

The water barrier 28 prevents flooding of the bomb shelter 10 by water or other liquids external of the bomb shelter 10. In addition, the water barrier 28 prevents the chamber 32 from being filled with surface liquids which would thereby prevent flushing liquid and filters from entering the chamber 32. The splash plate 58 has a free edge which is disposed over the passage 30 so that flushing liquids do not accumulate on the floor 12 adjacent the seal 26.

It will be appreciated that the container 34 need not be mounted directly above the doorway 18. The container 34 need only be supported in a position so that liquid may flow therefrom through the conduit 40 into the gutter 46. Hereinafter, the gutter 46 may be referred to as a dispersing member which distributes the liquid across the major face of the door 20.

The present invention may be embodied in other specific forms without departing from the spirit or essential attributes thereof and, accordingly, reference should be made to the appended claims, rather than to the foregoing specification as indicating the scope of the invention.

I claim:

1. A bombshelter comprising an enclosure, said enclosure including a wall having a doorway therein and a floor below said doorway, a door, means pivotally mounting said door in said doorway for movement between an open and a closed disposition, a dispersion member, a liquid supply tank mounted in a plane above the uppermost surface of said door so that liquid in said tank may flow from said tank to said dispersion member, means mounting said dispersion member so that liquid is dispersed on one major face of said door outside

5

10

25

of said enclosure, a waste receptacle including a waste receiving chamber located in a plane below the surface of said floor, said floor having a flow passage from the surface of said floor adjacent said one major face of said door to said chamber, a selectively operable valve for selectively controlling flow of liquid from said supply tank, an actuator for said selectively operable valve mounted within said enclosure, said door having an opening therein, a filter removably disposed within said opening, a filter guard mounted on said one major face of said door, said filter guard being juxtaposed to said opening so that said guard may direct replaced filters in the direction toward said flow passage, said flow passage having a cross sectional area greater than said filter so as to allow said filter to pass therethrough into said waste receiving chamber.

2. The bombshelter of claim 1 including a water barrier, said water barrier extending in an upright direction from the floor of said enclosure, said water barrier being spaced about the doorway of said enclosure, said water barrier being disposed to prevent surface liquid from entering said flow passage and allowing liquid from said supply tank passing down said major face of said door to enter said flow passage and to allow replaced filters to enter said flow passage.
